Inventor,
Seth E. Perkins, by
G. C. Kennedy, Attorney.

UNITED STATES PATENT OFFICE.

SETH E. PERKINS, OF WATERLOO, IOWA.

DOOR-OPERATING DEVICE.

1,247,322.

Specification of Letters Patent. Patented Nov. 20, 1917.

Application filed February 12, 1917. Serial No. 148,189.

To all whom it may concern:

Be it known that I, SETH E. PERKINS, a citizen of the United States of America, and a resident of Waterloo, Blackhawk 5 county, Iowa, have invented certain new and useful Improvements in Door-Operating Devices, of which the following is a specification.

My invention relates to improvements in 10 door operating devices, and the object of my improvement is to supply means for opening and closing swinging double doors, such as are usually employed in barns or garages, my device being combined with a 15 simple latching-means, and adapted to be actuated by means of the movement of a single operating element.

This object I have accomplished by the 20 means which are hereinafter described and claimed, and which are illustrated in the accompanying drawings, in which Figure 1 is a plan view of a pair of swinging double doors equipped with my improved device for opening and closing them, the full lines 25 representing the positions of the doors and operating parts when the doors are closed, and the dotted lines showing the positions of the same parts when the doors are opened; Fig. 2 is an elevation of said doors and of 30 the latching-means therefor as operatively associated with the said door opening and closing means.

Similar numerals of reference denote 35 corresponding parts throughout the several views.

The pair of doors 1 and 2 are mounted on hinges 5 and 6 respectively to swing to and from each other from the jambs 3 and 4. The door 1 has a catch 7 adapted to removably receive therein a latch-bar 10, the latter pivoted near its opposite end on a pivot-bolt 9 to the other door 2 and working within a limiting loop 8 on the latter door. The latch has on its end near said pivot-bolt 45 a vertical eye 11, in which is seated the downturned hither end of a connecting-rod 12, the opposite end of the rod being upturned to have its upturned end seated in a bearing-hole 16 in the middle of a swing-arm 15. The arm 15 is pivoted at one end on a pivot-bolt 14, loosely, said bolt being fixed in a bracket 13 on the jamb 4.

A braced bracket 17 is fixed on the opposite face of the door 1 near the jamb 3, 55 extending therefrom horizontally and pro-

vided with a terminal eye 18. A plate 21 is fixed on the like face of the door 2, and has a terminal eye 20. A connecting-rod 19 has down-turned ends movably mounted in said bearing-eyes 18 and 20.

In Fig. 1, the full lines show the positions of the parts when the doors are closed together. The arm 15 may be swung outwardly approximately 90 degrees to swing the doors open, placing the parts in the positions indicated by the dotted lines in the figure. Since the arm 15 is loosely pivoted at 14, and since there is some play between the pivotal connections of the connecting-rod 12 with both said arm and the eye 11 60 of the latch 10, the arm 15 can be swung downwardly slightly by the pressure of the hand alone, causing the rod 12 to actuate the latch 10 to lift the free end of the latter and detach it from said catch 7 before the 65 arm 15 is swung to swing the doors open. The arm 15 then being swung outwardly, swings open the door 2, which causes the connecting-rod 19, by means of its leverage 70 upon the bracket 17, to swing open the other 75 door 1.

To close the doors, the arm 15 is swung back to its former position, the actuating elements then acting to swing the doors into their closed positions, the latch 10 riding 80 over the inclined catch 7 and then becoming engaged with it by gravity.

It will be observed that there are relatively few actuating parts, inexpensive and easily operated by the single swing-arm 15. 85

Having described my invention, what I claim as new, and desire to secure by Letters Patent, is:

In combination, a pair of swinging doors, a bracket on one door, a connecting-rod pivotally connected between the outer end of said bracket and the other door, a catch on the opposite side of first-mentioned door, a latch pivotally mounted on the second-men- 90 tioned door and detachably engaged with 95 said catch, a depressible swinging arm, and a connecting-rod pivotally connected between said swinging-arm and said latch adapted to first disengage the latch from the catch when the swinging arm is depressed 100 and second to swing said doors open when the swinging arm is rocked in another plane. 105

Signed at Waterloo, Iowa, this 26th day of January, 1917.

SETH E. PERKINS.
